UNITED STATES PATENT OFFICE.

ISAAC STROUSE, OF NEW HAVEN, CONNECTICUT.

DESIGN FOR A CORSET.

SPECIFICATION forming part of Design No. 12,691, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for 5 Corsets; and I do hereby declare the following, when taken in connection with the accompanying drawing and the letters of reference marked thereon, to be a full, clear, and exact description of the same, and which said drawing constitutes 10 part of this specification, and represents a side view, showing the hip-section complete.

This invention relates to a design for the ornamentation of that part of a corset commonly called the "hip-section"—that is to say, the 15 part of the corset between the front and back, and which extends from under the arm down over the hip; and the design consists in the representation of cords or ribs in series, as shown in the accompanying illustration and 20 hereinafter described.

Transversely across the section, at the bot-

tom, is a series of ribs, *a*, a like series, *b*, at the top, and two intermediate series, *c* and *d*, leaving spaces between the respective series, the spaces between the series *a* and *d* filled by ribs 25 *e*, running diagonally downward and backward, the space between the series *d* and *c* filled by ribs *f*, running vertically, and the space between the series *c* and *b* filled by ribs *g*, running diagonally downward and forward, as shown in 30 the accompanying illustration.

I claim—

The design for the hip-section of a corset, consisting of the transverse series of ribs *a b c d*, with the intermediate space filled by the diagonal ribs *e g* and the vertical ribs *f*, as shown 35 in the accompanying illustration.

ISAAC STROUSE.
